M. SMULLEN

MARCEL WATER WAVER

Filed March 24, 1927

Mabel Smullen

By *Harry Bowen*

Attorney

UNITED STATES PATENT OFFICE.

MABEL SMULLEN, OF PORTLAND, OREGON.

MARCEL WATER WAVER.

Application filed March 24, 1927. Serial No. 177,852.

The invention is a device that one may readily insert in her hair to marcel or water wave the hair.

The object of the invention is to provide a simple and efficient device for marcelling or water waving the hair.

Another object of the invention is to provide a device by which one may give herself a perfect water wave.

Another object of the invention is to provide a marcelling or water waving device that may readily be inserted in or removed from the hair.

A further object of the invention is to provide a marcelling or water waving device that catches all of the hair, including the hair next to the scalp and the surface hair.

And a still further object of the invention is to provide a marcelling or water waving device that is of a simple and economical construction.

With these ends in view the invention embodies a curved band having hooks projecting from its under side and a small U shaped bar co-operating with the band and hooks.

Other features and advantages of the invention will appear from the following description taken in connection with the drawings, wherein:

Figure 1 is a view showing the device as it would appear in use.

Figure 2 is a side view of the device with part broken away.

Figure 3 is a plan view of the device.

Figure 4 is a view looking at the under side of the device.

In the drawings the device is shown as it would be made wherein numeral 1 indicates the band, numeral 2 the hooks projecting from the under side and numeral 3 the U shaped bar.

The band 1 is made as shown with flanges 4 and 5 at the ends which hold the bar 3. The flange 4 is provided with openings 6 in which the bar is slidably held and the flange 5 is provided with hooks 7 which hold the free ends of the bar 3. On the under side of the band 1 are the hooks 2 which are made as shown in Figure 2. It will be observed that these hooks may be stamped from the central portion of the band and shaped as shown. However it is also understood that these hooks may also be made in any other suitable manner. Openings 8 may also be placed in the side of the band if

desired. The bar 3 is formed as shown and provided with flat ends 9 which pass against the scalp to grip the hair next to the scalp as the device is being installed. It is also understood that the bar 3 may be made of any suitable design and of any suitable material.

It will be understood that changes may be made in the construction without departing from the spirit of the invention, one of which changes may be in the shape or design of the hooks under the band or at the end of the band, another may be in the use of other means for holding the bar 3 and still another may be in the general shape or design of the band or in the use of a band, or plurality of bands of different sizes.

To apply the waver, the bar is first withdrawn as far as possible, the body of the waver is laid on the hair where the first wave is to be made, and is then drawn in the direction in which the wave is to go, the hooks underneath catching all the surface hair. So that the hair close to the scalp will not be caught, the device is slightly lifted as it is pulled into place, and when the desired depth of wave is made, the waver is lifted free from the scalp still holding by means of the hooks all the surface hair that is to be waved. The bar is then pushed in, touching the scalp all the way and so catching the hair next to the scalp, until it reaches the end where it is caught in the clasps 7, in this manner being held close to the scalp after having drawn and held the surface hair in the shape of a Marcel wave. The next waver is applied contrary-wise.

Having thus fully described the invention, what I claim as new and desire to secure by Letters Patent is:

1. In a device of the class described, a curved band flanged at the ends, a plurality of hooks extending from the inner side of the band, other hooks in the flange at one end of the band and curved bars slidable in openings in the flange at one end of the said band and removably held in hooks at the other end of the said band.

2. In a device of the class described, a band, hooks on the under side of the band and slidable bars on each side of the hooks for holding the band to the hair and adaptable to be held by other hooks at the end of the band.

3. A band, means extending from one

side of the band for gripping and holding hair, or the like, slideable parallel bars at the sides of the said holding means, and hooks for readily holding and releasing the said bars.

4. In a hair waving device of the class described, a band curved to conform to the shape of the head, a plurality of hook shaped

members extending from the inner side of the band, a plurality of slideable bars under the band and at the sides of the said hook shaped members and means at the end of the band for holding the said bars. 10

In testimony whereof I affix my signature.

MABEL SMULLEN.
